UNITED STATES PATENT OFFICE.

RUDOLPH FLECK, OF MILWAUKEE, WISCONSIN.

BEDSTEAD.

SPECIFICATION forming part of Letters Patent No. 694,361, dated March 4, 1902.

Application filed February 4, 1901. Serial No. 45,880. (No model.)

To all whom it may concern:

Be it known that I, RUDOLPH FLECK, a citizen of the United States, residing at Milwaukee, county of Milwaukee, and State of Wisconsin, have invented new and useful Improvements in Bedsteads, of which the following is a specification.

My invention relates to improvements in bedsteads.

10 The object of my invention is to provide a more convenient and reliable means for the attachment of the side rails and the corner-posts than those heretofore employed, especial reference being had to bedsteads made 15 of iron.

In the following description reference is had to the accompanying drawings, in which—

20 Figure 1 is a top view of the corner-iron and a portion of one of the side rails, showing the corner-post in cross-section. Fig. 2 is a sectional view drawn on line xx of Fig. 1. Fig. 3 is a perspective view of one end of one of the side rails. Fig. 4 is a view of the inner face of the corner-iron and a portion of the corner-post, showing the recesses for the reception 25 of the side rail and with the engaged end of the side rail shown in cross-section. Fig. 5 is a sectional view on a line similar to that of Fig. 2, but showing a modified form of fastening.

30 Like parts are identified by the same reference-figures throughout the several views.

1 is the bed-post.

2 is a corner-iron, preferably formed integrally with the post. The corner-iron 2 is provided with a rounded outer surface which is provided with a flat open recess or channel 4.

35 The side rails of the bed are formed of angle-iron, and the vertical flange 5 of the rail 40 is extended beyond the horizontal flange 6 thereof. The extension 7 is curved at its outer end, as shown in Fig. 3, and is adapted to fit in the recess 4 of the corner-iron and may be secured therein by any suitable means, such 45 as the bolt and nut 8 and 9, respectively, (shown in Fig. 2,) or the hook-latch 10. (Shown in Fig. 5.) The inner face of the corner-iron is provided with horizontal channels, 50 as shown in Fig. 4, in which the horizontal flange 6 of the angle-iron is adapted to enter. It will be observed that I have provided two

of these channels, adapted to register with the horizontal flange of the side rails, whether the latter be at the top or bottom of the vertical flange. By loosening the fastening which 55 holds the side-rail extension 7 in the recess 4 the bedstead may be easily taken apart, but when in position will be held in such position with great rigidity, as the fastening merely 60 serves to keep the part 7 in position, while the sides of the recess 4 furnish the required support. It will also be observed that the curved extension 7 of the side rail substantially 65 engages two sides of the corner-iron, as its extreme end projects at nearly a right angle to the main portion of the rail. The bedstead is thus held together longitudinally by the side rails independently of the fastening and the bed supported vertically through the medium of the extension 7, engaging in the 70 recess of the corner-piece, the fastening being used to prevent a lateral separation of the side rail and corner-piece.

Having thus described my invention, what I claim as new, and desire to secure by Letters 75 Patent, is—

1. In a bedstead, the combination with one of the corner posts or legs; of a corner-piece secured thereto, and having a rounded and recessed outer surface; a side rail formed of 80 angle-iron, with its vertical portion extended and curved in conformity with said recess, and substantially engaging two sides of said corner-piece.

2. In a bedstead, the combination with the 85 corner posts or legs; of a corner-piece secured thereto, and provided with a rounded and recessed outer surface; a horizontal channel in its inner face; and side rails composed of right-angled flanges, one of said flanges being 90 extended and adapted to fit the recess in the rounded outer surface of the corner-piece, with the other flange registering with and engaging in the channel in the inner face of said corner-piece; together with means for securing 95 said side rail against lateral displacement.

In testimony whereof I affix my signature in the presence of two witnesses.

RUDOLPH FLECK.
